OTHER PUBLICATIONSU.S. Appl. No. 29/497,740, filed Jul. 28, 2014, Park et al.
(Continued)*Primary Examiner* — Antoine D Davis*(74) Attorney, Agent, or Firm* — Weaver Austin Villeneuve & Sampson LLP**CLAIM**

We claim the ornamental design for a wearable fitness band system, as shown and described.

DESCRIPTION

FIG. 1 is a top view of a wearable fitness band system.
 FIG. 2 is a bottom view of the wearable fitness band system of FIG. 1.
 FIG. 3 is a front view of the wearable fitness band system of FIG. 1.
 FIG. 4 is a back view of the wearable fitness band system of FIG. 1.
 FIG. 5 is a side view of the wearable fitness band system of FIG. 1; the wearable fitness band system of FIG. 1 is symmetric, so only one side view is shown.
 FIG. 6 is an isometric view of the wearable fitness band system of FIG. 1; and,
 FIG. 7 is an isometric view of the wearable fitness band system of FIG. 1 in a band-closed configuration, such as is formed when the ends of the band are pinned together as shown; the band portions of the wearable fitness band system are made from a flexible material, allowing them to be flexed into the configuration shown in order to be worn.
 Stipple shading is used in the accompanying Figures to convey surface contouring, not texture. The case portion in between the two band portions may have a transparent or translucent window that allows a display within the case portion to be seen by the wearer; the window may be smoked or tinted to obscure the internal components housed within the case portion (although permitting light from a display within the case portion to be transmitted through the window). This window is not stipple shaded in the accompanying pictures, but is rendered with diagonal line hatching to indicate transparency.

The logos, e.g., “Fitbit” (visible in FIG. 3), and text, e.g., “L/G” (visible on the inside of the wristband in FIG. 6), shown do not form part of the claimed design and are indicated using dotted lines and an absence of shading in order to show that they are unclaimed environmental subject matter.
